United States Patent Office.

THOMAS W. BARTHOLOMEW, OF NEW YORK, N. Y.

Letters Patent No. 101,211, dated March 29, 1870.

IMPROVEMENT IN SUSPENDERS.

The Schedule referred to in these Letters Patent and making part of the same.

To all whom it may concern:

Be it known that I, THOMAS W. BARTHOLOMEW, of New York, in the county of New York and in the State of New York, have invented a certain new and useful Swiveled or Duplex Suspender-Slide; and do hereby declare that the following is a full, clear, and exact description thereof, reference being had to the accompanying drawing making a part of this specification, in which—

Figure 1 is a plan view of my improved device as used, and

Figure 2 is a transverse section of the same on the line x x of fig. 1.

Letters of like name and kind refer to like parts in each of the figures.

My invention is intended for use upon suspenders at their intersection at the back, and has for its object the securing of said suspenders in their relative lateral positions without interfering with their longitudinal movement, to which end,

It consists in pivoting together two slides, through which the suspenders pass, substantially as hereinafter shown.

In the annexed drawing—

A and A' represent two suspenders at their crossing upon or at the back, having fitted loosely upon each a band or slide, B and B', consisting of a strip of sheet metal of any suitable width, the ends of which are bent inward and downward so as to embrace said suspenders, while, at the same time, allowing the latter to slide freely through said bands.

A rivet, C, passing loosely through the backs of the

slides at their center, radially, secures them together, and serves as an axial pivot, upon and around which said slides may revolve.

As thus constructed the device is complete; and being applied to a pair of suspenders (as shown in fig. 1,) serves to retain the latter in position and prevent the uncomfortable feeling occasioned by their slipping from the shoulders, without in the least interfering with the longitudinal motion necessary to enable each suspender to conform to the positions of the body.

The slides also permit the relative angles of the suspenders to change, as may be required to adapt the latter to different forms.

I am aware that suspenders or straps have heretofore been attached together by means of a pivot passing through a longitudinal slot within each strap, and do not, therefore, claim broadly such attachment of the same.

Having thus fully set forth the nature and merits of my invention,

What I claim as new, and desire to secure by Letters Patent, is

The pivoted slides or bands B and B', in combination with the straps A and A', substantially as and for the purpose specified.

In testimony that I claim the foregoing, I have hereunto set my hand this 19th day of February, 1870.

THO. W. BARTHOLOMEW.
